US00D918072S

(12) **United States Design Patent** (10) Patent No.: **US D918,072 S**
Umair et al. (45) Date of Patent: ** May 4, 2021

(54) **TRACKING DEVICE**

(71) Applicant: **Tile, Inc.**, San Mateo, CA (US)

(72) Inventors: **Muhammad Umair**, Pleasanton, CA (US); **Matthew Edward Kramer**, Los Gatos, CA (US); **Christopher Sean Wheaton**, San Francisco, CA (US)

(73) Assignee: **Tile, Inc.**, San Mateo, CA (US)

(**) Term: **15 Years**

(21) Appl. No.: **29/693,066**

(22) Filed: **May 30, 2019**

(51) LOC (13) Cl. **10-04**

(52) U.S. Cl.

CLAIM

The ornamental design for a tracking device, as shown and described.

DESCRIPTION

FIG. 1 is a top perspective view of a tracking device;

FIG. 2 is a bottom perspective view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front elevational view thereof; and,

FIG. 8 is a rear elevational view thereof.

The broken lines in the drawings showing portions of the tracking device are included for the purpose of illustrating environmental structure and form no part of the claimed design.

1 Claim, 8 Drawing Sheets
